UNITED STATES PATENT OFFICE.

CHARLES W. DUNHAM, OF EDGEWOOD BOROUGH, PENNSYLVANIA, ASSIGNEE TO THE UNION SWITCH & SIGNAL COMPANY, OF SWISSVALE, PENNSYLVANIA, A CORPORATION OF PENNSYLVANIA.

ELECTROCONDUCTING COIL.

1,340,027.

Specification of Letters Patent. Patented May 11, 1920.

Application filed March 6, 1917. Serial No. 152,765.

To all whom it may concern:

Be it known that I, CHARLES W. DUNHAM, a citizen of the United States, residing at Edgewood borough, in the county of 5 Allegheny and State of Pennsylvania, have invented certain new and useful Improvements in Electroconducting-Coils, of which the following is a specification.

My invention relates to electro-conducting 10 coils such as magnet coils, inductance coils or the like, and also to a method of constructing the same.

One object of the invention is the provision of a coil which is so constructed that 15 the two terminals are located on the outer surface of the coil and adjacent the middle thereof.

I will describe one form of coil, and method of constructing the same, and will 20 then point out the novel features thereof in claims.

In the accompanying drawings, Figure 1 is a view showing in longitudinal section one form of coil embodying my invention. 25 Fig. 2 is a sectional view taken on the line II—II of Fig. 1, looking in the direction of the arrow, and showing the direction in which one of the sections of the coil is wound. Fig. 3 is a sectional view taken on the line III—III of Fig. 1, looking in the direction of the arrow, and showing the direction in which the other section is wound. Fig. 4 is a view showing in side elevation and partly in section, the coil 30 shown in the preceding views together with one form of lightning arrester applied thereto.

Similar reference characters refer to similar parts in each of the several views.

40 Referring first to Fig. 1, the coil here shown comprises two sections W and W', the two terminals of each section being brought out at the same end of the section. These two sections are mounted in axial 45 alignment, with the terminal ends in juxtaposition, and are separated by a space C. As here shown, the sections are mounted on a straight tubular support T of insulating material which is adapted to receive a soft 50 iron core, although I do not desire to limit myself to this particular means for mounting the sections.

The two inner terminals E and E' of the sections are electrically connected in the space C, as shown in the drawing, so that 55 the outer terminals F and F' constitute the actual terminals of the coil as a whole. The sections are so wound, and are so mounted with relation to each other, that when current enters at one terminal F or F' and 60 leaves at the other, the magneto-motive forces produced by the two sections are in the same direction. That is, when the sections are mounted in proper relative position, the two sections are wound in opposite directions, as shown by Figs. 2 and 3. 65 This may conveniently be accomplished by winding the two sections in similar manner, that is, in the same direction and with the terminals taken out at the same end, and 70 then placing these sections end to end with their terminal ends in juxtaposition.

The terminals F and F' may be provided with flexible leads if so desired, and these leads, as well as the connected ends E and 75 E', may be wound around the tube T in the space C, and subsequently protected by cord or other suitable covering.

It will be apparent that the two actual terminals F and F' are located adjacent the 80 middle of the coil, and that consequently the danger of grounding is reduced, the "end insulation" of the coil as a whole is improved, and the construction of an electromagnet comprising two such coils, is simplified. Furthermore, both actual terminals 85 F and F' are on the outer surface of the coil, so that in the event that one of these terminals becomes broken it is only necessary to unwind one or two turns of the wire, 90 and affix a new flexible lead if such leads are employed.

A coil constructed in accordance with my invention is well adapted to receive a simple form of lightning arrester, as shown in Fig. 95 4. The arrester A, shown herein, comprises two overlapping conducting strips S, S', the ends of which are embedded in the sections W and W' respectively between the two outermost layers of wire, each strip 100 being preferably in electrical contact with the wire in the outer layer but insulated from the inner layer by the usual insulation on the wire and also by a block B of insula-

ing material. The strips S and S' are insulated from each other by a thin block B' of insulating material. By properly proportioning the strips and insulation blocks of the arrester, it will be evident that when lightning attempts to traverse the coil C, it will be shunted from the coil and caused to select the more direct path afforded by the arrester, thereby preventing injury to the coil. It will be noted that the lightning arrester is conveniently and safely carried by the coil in an unobstructing position.

Having thus described my invention, what I claim is:

1. In combination, a single electro-conducting coil comprising two sections similarly wound and each having both terminals at the same end, said sections being mounted in axial alinement and in spaced relation, and arranged so that the terminal ends are in juxtaposition, the inner ends of the two sections being electrically joined, and a continuous core of magnetizable material fixed with relation to said sections and pass-

ing through said sections and through the 25 space between the sections.

2. In combination, a single electro-conducting coil comprising two sections mounted in axial alinement and spaced relation, the terminals of said sections all 30 being on the adjacent ends of the sections and the inner terminals being electrically connected, said sections being so wound and so relatively arranged that when current enters at one outer terminal and leaves at 35 the other magneto-motive forces produced by the two sections are in the same direction, and a continuous core of magnetizable material fixed with relation to said sections and 40 passing through said sections and through the space between the sections.

In testimony whereof I affix my signature in presence of two witnesses.

CHARLES W. DUNHAM.

Witnesses:

A. HERMAN WEGNER,
R. GEORGE RUDMAN.
